UNITED STATES PATENT OFFICE.

ALFRED BRUNNER, OF LEIPZIG-EUTRITSCH, AND WILHELM SCHÖNDELING, OF LEIPZIG-GÖHLIS, GERMANY, ASSIGNEES TO ADOLF BLEICHERT & COMPANY, OF LEIPZIG-GÖHLIS, GERMANY.

APPARATUS FOR QUENCHING AND CONVEYING GLOWING MATERIALS.

1,085,845.

Specification of Letters Patent.

Patented Feb. 3, 1914.

Application filed April 30, 1910. Serial No. 558,593.

To all whom it may concern:

Be it known that we, ALFRED BRUNNER and WILHELM SCHÖNDELING, subjects of the Duke of Brunswick and the King of Prussia, 5 Germany, respectively, residing at Leipzig-Eutritzs and Leipzig-Göhlis, Germany, respectively, have invented new and useful Improvements in Apparatus for Quenching and Conveying Glowing Materials, of which 10 the following is a specification.

This invention relates to an apparatus for quenching and conveying glowing materials and more especially to apparatus of this character employed in connection with coke.

5 In view of the local conditions before the furnace-batteries it is often impossible to carry out the quenching of coke, etc., by lowering the carrier intended for the material into the water-tank. In the present invention 20 an alteration has therefore been made by arranging the water-tank for raising and lowering, the quenching process being carried out by its actuation.

The arrangement can be seen on the 25 drawing.

Figure 1 shows the same with separate carrier and water-tank, whereas Fig. 2 shows a coke quenching vessel with combined carrier and water-tank.

30 The bucket *b* for taking up the coke discharged from the ovens is on rail *a* and arranged to travel along the oven-battery. The runway for the water-tank runs parallel to the rail *a* and consists of the car-frame

35 *c* and the tank *d* for the water. The latter slides in guides of the frame *c* and can be raised and lowered by means of winches *e* with common drive through a shaft *g*, which are fitted on the car-frame. As counterpoise 40 to the weight of the tank and water for quenching purposes suitable counter-weights are provided.

The method of working is as follows:— The coke-bucket *b* is run under the mouth of the 45 retort to be emptied, under which the water-car *c* has been already placed. The tank *d* is then raised somewhat so that the water reaches a certain height in the coke-bucket, in order to temper the fall of the

coke and thus prevent a breakage of the 50 pieces. As soon as the bucket has been filled the water-tank is more or less slowly raised by the winches *e* until the top layer of coke is also under water. When a sufficient time has elapsed the water-tank is again lowered 55 and the coke-bucket containing quenched coke is conveyed to the coke bunker, storage ground or other arrangement.

The quenching of coke by the above described method is also possible on plants 60 even if the height of the available space before the ovens only allows of the employment of a coke quenching carrier, which is a combination of carrier and water-tank, as shown in Fig. 2. Here the arrangement is 65 again made that the water-tank *d* in frame-guides can be raised after the discharge of the coke into the carrier to inclose the same, and then lowered after the quenching of the coke. In this case water-tank and coke-carrier can either be transported together or 70 the coke must be transferred for transport on to a conveyer-band arranged alongside the quenching tank.

Apart from the saving in space in the 75 above arrangement this method has the advantage that, in drawing off the coke, especially in large quantities, the water is not forced out of the tank and the steam developed can be made to escape more freely, and 80 forms no hindrance to the quenching, but can even be turned to account in quenching the glowing coke.

What we claim as our invention and desire to secure by Letters Patent of the 85 United States is:—

1. A coke quenching device consisting of a perforated coke carrier adapted to be moved to receive coke from the retorts, a traveling member operatively associated 90 with said carrier and movable therewith, a water tank carried by said traveling member, and means for raising and lowering said water tank with respect to said carrier.

2. A coke quenching device, consisting of 95 a perforated coke carrier, a traveling frame provided with guides and a water tank which slides on said guides.

3. A coke quenching device, consisting of a perforated coke carrier, a traveling frame provided with guides and a water tank which slides on said guides, winches to actuate the tank and counterweight for balancing said tank.

In testimony whereof we have signed our

names to this specification in the presence of two subscribing witnesses.

ALFRED BRUNNER.

WILHELM SCHÖNDELING.
